UNITED STATES PATENT OFFICE.

JOHN E. SHEPHERD, OF CHICAGO, ILLINOIS, ASSIGNOR TO AUTOMATIC FIRE PROTECTION COMPANY, A CORPORATION OF MAINE.

FIRE-PROTECTION SIGNAL SYSTEM.

No. 828,047.

Specification of Letters Patent.

Patented Aug. 7, 1906.

Application filed September 6, 1904. Serial No. 223,459.

To all whom it may concern:

Be it known that I, JOHN E. SHEPHERD, of Chicago, in the county of Cook and State of Illinois, have invented certain new and useful Improvements in Fire-Protection Signal Systems; and I hereby declare that the following is a full, clear, and exact description thereof, reference being had to the accompanying drawings, which form part of this specification.

My invention relates to improvements in fire-protection signal systems, and has for a salient object to provide means directly associated with an automatic valve of a fire-extinguisher system adapted to coöperate with certain electrical devices for causing the transmission of an alarm in a signal-circuit when the valve is opened for a predetermined time.

Other and further objects of my invention may best be ascertained from the following description, taken in conjunction with the accompanying drawings, wherein—

Figure 1 is a sectional view of an automatic valve and associated devices embodying my invention, showing diagrammatically in suitable circuit relation devices constituting the electric-alarm circuit. Fig. 2 is a fragmentary section of part of the valve, showing the time-switch in end elevation. Fig. 3 is a detail of the signal-box construction.

Referring now to the drawings, A indicates the casing of an automatic variable-pressure or check valve of well-known construction, in which a is a moving member or valve proper movable on a right line from and toward its seat a' and having its stem a² guided in a suitable bearing a³.

a⁴ indicates a projection from one side of the casing.

The valve construction illustrated is one well known in the art and needs no detailed description. I do not intend, however, to limit the use of my invention to such a valve, as it will become apparent that it is capable of use in conjunction with any automatic valve a part whereof moves in opposite directions in opening and closing.

B indicates in general a time-switch mounted within the valve-casing A and directly associated with the movable member a of the valve, arranged when in normal or passive

condition to close an electric circuit and when moved by the action of the valve to 55 abnormal or active position to first break said circuit and subsequently after the lapse of a definite interval of time to again make the circuit.

In the specific construction shown the 60 time-switch B comprises a frame b, pivoted, as at b', to the projection a⁴ of the valve-casing and arranged to be maintained by gravity in constant contact with the top surface of the valve member a. Mounted upon the 65 frame b' is a device comprising two chambers b² and b³, connected for communication by a restricted passage b⁴. The device described is preferably of glass and is adapted to constantly contain a body b⁵ of electrically-conductive mobile material, such as mercury. The parts are preferably so arranged that when the valve a is in normal closed position and the time-switch B consequently in its lowest position substantially all of the mercury lies in the chamber b²; but when the valve a is raised to dotted-line position and the frame b is thereby tipped the mercury runs into the chamber b³ to substantially fill the same.

Contact parts adapted for inclusion in electric circuits are associated with the device to be affected by the flow of mercury, and in the specific construction two pairs of contacts b⁶ and b⁷ are arranged within the respective 85 chambers b² and b³, the contacts b⁶ being normally electrically connected through the mercury and the contacts b⁷ being normally open or disconnected. It will be apparent now that when the switch is tipped to dotted-line position the mercury flows from the chamber b² to the chamber b³ through the restricted passage b⁴, so that in time connection between the contacts b is broken, and after the lapse of a definite interval of time connection is made between the contacts b⁷. The contacts b⁶ and b⁷ are connected in parallel in a circuit C, which includes a suitable 90 source of electric supply c and an electromagnet c'.

The electromagnet c' is arranged to actuate the controlling mechanism of a suitable signal-box arranged in a signaling-circuit, a preferred arrangement of signaling devices being shown in Fig. 1.

The signal-box preferably comprises a nor-

mally wound spring-motor, the motor-train being arranged to drive synchronously two number-wheels d and d' , each comprising, preferably, a toothed portion and a peripheral raised portion, the peripheral raised portion of each wheel corresponding in position and extent with the toothed portion of the other wheel. Associated with the wheel d are the spring d^2 and contact d^3 , and with the wheel d' are associated the pen d^4 and contact d^5 .

The controlling mechanism for the box may be of any suitable construction arranged for control by the electromagnet c' and adapted to operate in substantially the manner of a construction which I will now describe.

d^6 indicates a rotating part driven by the motor-train and provided with an annular flange d^7 having formed therein, at two different elevations or diametrically opposite points, the notches d^8 and d^9 . The rotating part d^6 is preferably so geared relative to the number-wheels d d' that it makes one half-revolution to each complete revolution of the said number-wheels.

The controlling device proper comprises, preferably, a pivoted lever e , to which is attached the armature e' of electromagnet c' , and provided at its end with two arms e^2 and e^3 , each having thereon a finger adapted for engagement with one of the notches d^8 or d^9 of the rotating part d^6 of the motor. As illustrated in Fig. 3, the arrangement is such that the finger of the arm e^2 can only engage with the notch d^8 and the finger of arm e^3 can only engage with the notch d^9 . It follows that when the armature e' is attracted by its magnet c' the motor mechanism of the box will be held in inactive position by the engagement of the finger e^2 with the notch d^8 . If, however, the armature be released and retracted by its spring, the mechanism is free to make a half-revolution until the notch d^9 registers with the finger of arm e^3 , when the mechanism is again stopped. During this half-rotation of the wheel d^6 the number-wheels d and d' make one revolution. If, now, the armature be again attracted, the parts tend to restore themselves to their initial position and the wheel d^6 makes another half-revolution before the finger of arm e^2 again engages with the notch d^8 , and the number-wheels d and d' make another revolution. It will be apparent that as the movements of the armature are controlled by the magnet c' the operation of the box is responsive to the operation of the magnet-controlling time-switch B. The signal-circuit may be arranged in any suitable manner, but I prefer that it be connected as follows: from a battery F, by wire 5, through two parallel branches to the respective pens of the wheels d d' , the one branch extending by wire 6 to the pen d^2 , from its contact d^3 by wires 7 to a contact-

point 8', with which the magnet-armature e' contacts when the armature is in attracted position, and from the pivot-point of said armature by wire 9, back to the main circuit. The other branch extends by wire 10 to pen d^4 and contact d^5 and thence by wire 11 to a point of juncture with the wire 9, whence the circuit extends by wire 12 to a suitable signal-recording device G and from the opposite terminal of said signal-recorder by wire 13, back to the central battery F.

The operation of the system described is as follows: When the automatic valve a is raised by the commencement of flow of the water through its riser or other pipe, it acts directly upon the time-switch B to raise the same to the dotted-line position. Consequently the mercury flows from the chamber b^2 to the chamber b^3 , as heretofore described, breaking the circuit C at points b^6 , so that the magnet c' is de-energized and its armature is retracted by the spring, thereby tripping the signal-box, as heretofore described. The number-wheels d d' of the signal-box make one round, and then the motor is stopped. It is to be noted, however, that the movement of the armature breaks the branch of the circuit containing the pen and contact d^2 and d^3 at contact-point 8', so that a signal is transmitted to central station only from the wheel d' , and the recorder G at the central station accordingly indicates the number of the wheel d' , followed by a long dash of "rundown." When now sufficient mercury has flowed through the obstructed passage b^4 to effect connection between the points b^5 , the magnet-circuit C is again closed and the magnet-armature e' attracted, again actuating the signal-box, so that its number-wheels make one round, as heretofore described. During this revolution of the number-wheels it is to be noted that both branches of the signaling-circuit are closed, so that each wheel transmits its number, and with the arrangement of teeth shown in the drawings the signal received at central station will be the number of the box thrice repeated. It will further be apparent that should the valve a be opened and immediately closed, as by a "kick" or sudden variation in the water-pressure in the pipe containing the valve, no signal is transmitted, as the raising and lowering of the time-switch B in rapid succession does not permit sufficient mercury to flow from one chamber to the other through the restricted passage to cause the breaking of the circuit at the point b^6 ; but in case the valve a is maintained in open position for any length of time the time-switch arrangement insures that the proper conditions must inevitably occur in the magnet-circuit to activate the signal-box to transmit its proper and full signal to indicate the continued flow of water in the piping system.

While I have herein described in some detail a specific construction and arrangement of signaling devices and other associated parts which I prefer to employ in the installation and operation of my system, it will be apparent that equivalent devices might be used without departing from the spirit and scope of my invention, and I do not desire to be understood as restricting myself to the specific construction and arrangement herein illustratively shown further than as specified in the claims.

I do not claim as my invention, in combination with a valve or other part responsive to pressure in the fire-extinguisher system and with an electric alarm mechanism, a watertight chamber into which the terminals of the alarm-circuit extend, located in the waterway or, more specifically, in said chamber for controlling the alarm mechanism, nor do I claim a construction of the character described wherein the water-tight chamber is movable by the valve and contains as a circuit-controlling means a shifting body, whether of mercury, other fluid, or matter in some other state, and, further, I do not claim as my invention the broad idea of associating in combination a chamber, a fluid-body contained in the chamber and adapted to shift therein, an alarm mechanism operatively associated with said body, and means controlled by pressure in the system for shifting said body and causing it to condition the alarm mechanism to operate whether with or without retarding means for the shifting body, nor a combination, as above described, whereby the shiftable body is shifted in one direction to cause it to condition the alarm mechanism to operate and in the opposite direction whereby its normal condition is re-established.

Having thus described my invention, what I claim, and desire to secure by Letters Patent of the United States, is—

1. The combination with a valve of a fire-extinguisher system, of means for indicating the flow of water through said valve comprising a signaling device, and a time-switch for controlling said signaling device, mounted within the valve-casing and arranged to be actuated directly by the movable element of the valve. 45

2. In combination with a valve of a fire-extinguisher system, means for indicating the flow of water through said valve comprising a signaling device, and a time-switch for controlling said signaling device mounted within the valve-casing, and associated with the movable element of the valve for actuation thereby. 50

3. The combination with an automatic valve of a fire-extinguishing system, of a signal device, a circuit therefor, a time-switch for controlling said signal device comprising a frame pivoted within the valve-casing and associated directly with the valve proper for movement therewith, a device carried by said frame comprising two chambers connected by a restricted passage, contacts comprising part of the circuit aforesaid within the said chamber, and a body of mobile, electrically-conductive material in said chambers arranged when said switch is moved to vary the conditions of the electric circuit to actuate the signaling device. 65

In testimony that I claim the foregoing as my own I affix my signature in presence of two witnesses.

JOHN E. SHEPHERD.
